(No Model.)

I. W. LINCOLN.

FIRE ESCAPE.

No. 267,696.

Patented Nov. 21, 1882.

UNITED STATES PATENT OFFICE.

ISAAC W. LINCOLN, OF ST. JOSEPH, MISSOURI.

FIRE-ESCAPE.

SPECIFICATION forming part of Letters Patent No. 267,696, dated November 21, 1882.

Application filed June 26, 1882. (No model.)

To all whom it may concern:
Be it known that I, ISAAC W. LINCOLN, a citizen of the United States, residing at St. Joseph, in the county of Buchanan and State 5 of Missouri, have invented certain new and useful Improvements in Firemen's Elevators; and I do hereby declare that the following is a full, clear, and exact description of the same, reference being had to the annexed drawings, making a part of this specification, and 10 to the letters and figures of reference marked thereon.

Figure 1 of the drawings is a front elevation of a building showing the application of my 15 invention. Fig. 2 is a sectional elevation of the front wall of a building showing the application of my invention. Fig. 3 is a detail view of the gearing which is connected to the reel for holding it at any desired position; 20 Fig. 4, a detail view of one of the spring-holding devices for holding the wire cords or ropes when not in use; Fig. 5, a similar view of the device, showing the wire ropes in position when held thereby; and Fig. 6, a detail view of one 25 of the pulleys for holding the wire cord, provided with an alarm.

The object of the present invention is to provide means by which firemen, either with or 30 without hose, can be readily and quickly elevated to the roof or other portion of a burning building, thereby enabling them to locate a fire; also, to flood the structure in the exact locality wherein it is burning, irrespective of height of said building; also, to use the device for rescuing the inmates thereof, as 35 required. These objects I attain by the means substantially as shown in the drawings, and hereinafter described and claimed.

In the accompanying drawings, A represents a building having connected to its roof 40 or upper portion iron brackets B, of any suitable form and construction, to which are suspended pulleys C. Over the pulleys C pass wire cords D, which, when not in use, are held 45 against the building by means of spring-holding devices consisting of corrugated spring-plates E, fastened to spikes a, which are driven in the wall of the building, as more clearly shown in Fig. 5. It will be noticed

that the corrugated plates E are connected to 50 the spikes a at one end only, and being of spring metal the wire cords can be pressed out and detached therefrom by the person on the ground by pulling them laterally in the direction of the free ends of the plates. The 55 pulleys C are each provided with an alarm, consisting of a steel spring, b, attached to the axle of the wheel or roller, which turns therewith, and when the wire cord is pulled in either direction it strikes one of the two pins c, and 60 by the continued turning of the wheel or roller the spring will fly from the pin and with sufficient force to strike an alarm against the bell d.

By the employment of the alarm, burglars 65 or other unauthorized persons are prevented from tampering with the wire ropes without it being known. These wire ropes or cords D, when not in use, are at all times designed to be held against the building, and are for the 70 purpose of pulling the wire ropes F through pulleys C, after which the ropes are unfastened from cords D and fastened to a suitable car, G. The other end of wire rope F is at all times fastened to a suitable reel, H, 75 upon a carriage, I, and is wound upon or unwound from the reel, thereby raising or lowering car G, as desired, said car being guided in its course by guy-ropes K.

The car G is provided with grab-hooks, by 80 which it may be fastened to any opening desired, and the reel may have gearing e f and pawl g for turning it and holding it stationary when desired.

Any suitable reel with a coil of wire rope 85 of sufficient length may be employed and adapted for attachment to any hook-and-ladder truck or hose-reel cart or carriage, or may be used on a separate truck built for the purpose.

Although the invention is more particularly 90 intended to elevate the firemen, with or without the hose, to any point or height, for the purpose hereinbefore described, the car can be also used for or as a fire-escape to rescue the inmates from the burning building.

Having now fully described my invention, 95 what I claim as new, and desire to secure by Letters Patent, is—

The brackets B, having suspended therefrom pulleys C, carrying wire cords D, in combination with the spikes a, driven in the building and provided with the corrugated 5 spring-plates E, for retaining the wire cords when not in use against the building, substantially as and for the purpose set forth.

In testimony that I claim the above I have hereunto subscribed my name in the presence of two witnesses.

ISAAC W. LINCOLN.

Witnesses:

JOHN A. DOLMAN,
F. M. TUFTS.
